CURTAIN ROD

Angelo Baretella, Union City, N. J.

Application October 7, 1947, Serial No. 778,285

7 Claims. (Cl. 211—105.6)

1

My invention relates generally to curtain rods, and specifically to self-attaching curtain rods.

It is among the objects of my invention to provide a curtain rod which is self-attaching to a window frame and needs no attachment brackets.

It is another object of my invention to provide a curtain rod over which the hems of curtains may be drawn without risk of damaging the fabric.

Yet another object of my invention is to provide a curtain rod which is simple in form, inexpensive, easy to construct and durable.

The drawings show a preferred embodiment of my invention:

Figure 1 is an elevational view of my curtain rod assembled; and

Figure 2 is a partial sectional view of my curtain rod.

Figure 3 is a partial sectional view of my curtain rod in affixed position.

Referring now to the drawings in detail, my curtain rod provides a solid cylindrical rod member or inside rod 11. Another cylindrical rod member or outside rod 12 is also provided. This outside rod 12 is hollow, having an opening or cavity 13 for a suitable portion of its extent; into the cavity 13, the end of the inside rod 11 is inserted. The cavity 13 contains a spring 14 which urges the rods 11, 12 away from each other. Each end 15 of the rods 11, 12 is slightly larger in diameter than the rods 11, 12 themselves. Thus, a shoulder 16 is formed which acts as a stop for the sleeve 17, by engaging a flange 18 on the sleeve. The ends or enlarged portions 15 have openings 28 in them into each of which a pin 19 is inserted. The pin has a point 22 at the end. The pin carries a spring 20. This spring 20 engages the end 15 and also bears on a cap or shield 21. The shield 21 is arranged in threaded engagement with the sleeve 17, the shield 21 and the sleeve 17 constituting a sheath for the pin 19. The cap 21 is of such extent that the spring 20 causes it to shield the pin 19. The cap 21 has an opening or aperture 23 through which the pin 19 may extend when the sleeve is moved toward the opposite end of the rod 11; such movement compresses the spring 20 which normally urges the shield 21 to sheathing position shown in Figure 2.

The use of my curtain rod is as follows: The curtains are first positioned on the rod by inserting the rod through the hem. The spring 20 normally urges the shield 21 to a position where the pin 19 is covered; thus there is no danger

2

of the curtain material snagging on the pin 19.

When the curtain has been positioned on the rods 11, 12, the inside rod 11 and the outside rod 12 are telescoped to compress the spring 14. The rod is then positioned so that its ends are opposite the points of the window frame 25 where it is desired that the rod affix itself. The ends of the rod are then allowed to make contact with the window frame. The spring 14 urges the inside and outside rods 12 away from each other, so that the points 22 are projected into the wooden window frame 25. If a metal window frame is involved, the points may be projected into holes therein.

The spring 20 is of very light construction so that the pressure exerted by the strong spring 14 easily overcomes the pressure exerted by the spring 20. This is brought about when the ends 26 of the shields 21 are pressed up against the window frame 25 as the spring 14 urges the rods 11, 12 apart. The light easily compressible spring 20 is compressed by the face 27 when the end 26 bears on the frame 25 and the shield 21 unsheathes the point 22. The point 22 digs into the window frame and the rod is in place without the aid of auxiliary fixtures.

Nevertheless, the points 22 are kept shielded by the action of the spring 20 on the shield 21 when the curtains are being placed on the rods.

The foregoing drawings and description present merely a preferred embodiment of my invention for many changes in the construction, selection and arrangement of the parts may be made within the scope of the appended claims without departing from the spirit of the invention.

I claim:

1. A curtain rod comprising an outer rod with a cavity at one end and an enlarged portion at the other end, an inner rod with an enlarged portion at one end and the other end adapted to enter the cavity in the outer rod, a spring positioned in the cavity in the outer rod and normally urging the inner rod out of the cavity, pins connected to the inner and outer rods at their ends, flanged sleeves engaged with the enlarged portions of the inner and outer rods, caps with a central orifice for the pins connected to the sleeves, and springs positioned within the sleeves in engagement with the caps and rods normally urging the caps into sheathing relation with the pins.
2. A curtain rod comprising a rod having a cavity, another rod having an end telescoping into said cavity, a spring positioned in the cavity

and normally urging the rods apart by engaging the ends thereof, a pin connected to one of the rods, a sleeve for covering the pin slidably connected to the rod, an apertured cap connected to the sleeve, and a spring mounted on the pin within the sleeve and normally maintaining the cap and sleeve in sheathing relationship with the pin.

3. A curtain rod comprising a rod member, a pin attached to the rod member at one end thereof, a sleeve slidably connected to the rod member, and a spring mounted on the pin within the sleeve and normally maintaining the sleeve in sheathing relationship with the pin, another rod member telescoping in a cavity in the first rod member, and a spring normally urging the rod members apart mounted in said cavity in the rod and bearing on the end of the other rod.

4. A curtain rod comprising a rod member, a pin attached to the rod member at one end thereof, an enlarged portion at one end of the rod member defining a shoulder, a sleeve slidably connected to the enlarged portion, a flange on the sleeve and a spring mounted within the sleeve and normally maintaining the sleeve in sheathing relationship with the pin, a second rod member telescoping in a cavity in the first rod member, and a spring normally urging the rod members apart mounted in the cavity in the first rod and bearing on the end of the other rod.

5. A curtain rod comprising telescopically connected outer and inner rods, a pin mounted on the end of one rod and a spring pressed retractable sheath normally coextensive with the pin and slidably mounted on said rod, and a spring normally urging the outer and inner rods apart mounted in a cavity in the outer rod and engaging the end of the inner rod.

6. A curtain rod comprising a first rod mem-

ber, a pin mounted on the end of the said rod member, and a spring pressed retractable sleeve normally coextensive with the pin and slidably mounted on the rod member, another rod member telescopically connected to the first rod member, and a spring normally urging the rod members apart mounted in a cavity in said first rod and engaging the end of the other rod.

7. A curtain rod comprising a rod member, a pin mounted on the end of the rod member, a sleeve slidably mounted on the rod member, and a spring mounted on the pin within the sleeve and engaging the end of the rod member and the sleeve, said spring normally urging the sleeve into sheathing relationship with the pin, another rod member telescoping within a cavity in the first rod member, and a spring mounted in the cavity in said first rod member and engaging the end of the other rod member, said spring normally urging the rod members apart.

ANGELO BARETTELLA.
